United States Patent Office

Des. 197,197
Patented Dec. 24, 1963

197,197

BOAT

Richard E. Bennett, Tiptonville, Tenn.

Filed Sept. 4, 1962, Ser. No. 71,524

Term of patent 3½ years

(Cl. D71—1)

Fig. 1

Fig. 2

Fig. 3

Fig. 5

Fig. 4

FIG. 1 is a top plan view of the boat showing my new design.

FIG. 2 is a side elevational view thereof.

FIG. 3 is an elevational view of the opposite side thereof.

FIG. 4 is a rear elevational view thereof; and

FIG. 5 is a cross sectional view thereof taken on the line 5—5 of FIG. 1.

I claim:

The ornamental design for a boat, substantially as shown.
